UNITED STATES PATENT OFFICE.

CHARLES A. LIEB, OF NEW YORK, N. Y., ASSIGNOR TO THE SHERIDAN
BOOK-BINDERS SEWING MACHINE COMPANY, OF SAME PLACE.

BOOK-SEWING MACHINE.

SPECIFICATION forming part of Letters Patent No. 351,328, dated October 19, 1886.

Application filed January 28, 1886. Serial No. 190,085. (No model.)

To all whom it may concern:

Be it known that I, CHARLES A. LIEB, a citizen of the United States, residing at New York, in the county and State of New York, 5 have invented new and useful Improvements in Sewing-Machines for Books, of which the following is a specification.

This invention relates to machines for sewing together the "signatures" of books; and 10 it consists in a mechanism for such sewing, and also for forming the channel for the "band" by punching a series of openings into the back of the signature being sewed, all in one operation.

15 The novel features in the construction of the above mechanism are fully pointed out in the following specification and claims, and illustrated in the accompanying drawings, in which—

20 Figure 1 is a section of my machine in the plane x x , Fig. 2. Fig. 2 is a section in the plane y y , Fig. 1. Fig. 3 is a section on the line z z , Fig. 5. Fig. 4 is a section on the line x' x' , Fig. 3. Fig. 5 is a section on the line 25 y' y' , Fig. 3. Fig. 6 is a section on the line z' z' , Fig. 3. Fig. 7 is a side view of a portion 30 of a signature, showing the channels cut by the needle-punches. Fig. 8 is a section on the line z z , Fig. 5, showing the signature-carrier closed. Fig. 9 is a similar section showing the 35 signature-carrier open.

Similar letters indicate corresponding parts.

In the drawings, the letter A designates the frame, to which are secured the bearings B for the rock shaft C, on which the oscillating arms D are mounted. In the outer ends of these arms are formed bearings E, for the gudgeons a , Fig. 5, projecting from plates b, between which the signature-carrier F is secured. In the example shown in the drawings, the plates b, with the signature-carrier F, are held in a vertical position during the oscillations of the arms D by guide-arm c, mounted on the gudgeon a , the free end of which carries an anti-friction roll, d, which engages a stationary cam, G, secured to the frame A. The oscillating motion is imparted to the arms D by a bell-crank lever, H, pivoted to the frame at J', one end of which engages a crank, J, mounted on the 50 rock-shaft C, while its other end is held in con-

tact with a cam, K, mounted on the main shaft L, by a coiled spring, s, Fig. 5.

In operating my machine the signature to

be sewed on is placed by the attendant on the carrier F when the latter is in the position indicated in dotted lines in Fig. 1. By the mechanism above described the carrier is brought to the position shown in full lines in said figure against the stop-plate A', running across the machine and under the combined punching 55 and sewing mechanism, in which position it is automatically held by a spring-bolt, e, Fig. 4, which is mounted in the stop-plate. In this combined punching and sewing mechanism the needles f, which usually are pointed, 60 are blunt and act as punches, passing through the signature and into the opening g, Figs. 3, 4, 8, and 9, in the upper edge of the carrier F, which act as dies, by which means a piece is cut out from the back of the signature, Fig. 70 7, of sufficient size to form a channel for the band. A groove is formed on each side of the needle above the eye, in which lies the needle-thread, which in this machine forms the band for the book when the needle passes through 75 the openings g in the carrier, by which means said thread is protected against chafing or being cut by the sharp edge of the opening g. The needles are secured to a needle-bar, M, running across the machine, and to it are 80 connected rods B', having roller-studs at their lower ends, that engage grooves in the cams K and N, Fig. 2, which are of a proper shape to give the needle the necessary up-and-down and looping motion. The needles, which may 85 be secured to the needle-bar in any manner, pass through holes in the stop-plate A', which holes serve as guides when the needles move down, and as strippers when they move upward and out of the signature, preventing the 90 same from moving up with the needles. The tension C', the take-up D', and the shuttle E', all of which are of common construction, together with the needles, form an ordinary organized sewing mechanism, and I do not desire to confine myself to the exact construction 95 described herein.

To permit the trimming of the edges of the book after it is sewed, it is necessary that the shuttle-thread should not extend to the outer 100

edge of the book, so as not to be cut by that operation, and for that reason it has been customary to slit the back of the signature from its outer edges to where the two outer needles 5 pierce it to admit the shuttle-thread. For this purpose I employ two knives, b' , Fig. 2, one at each end of the carrier F , which pass into recesses in the stop-plate, and cut the desired slits as the carrier strikes against the stop- 10 plate.

As the stitch, necessary for the work done by this machine, will permit the passage of the shuttle from either direction, the shuttle-carrier is so timed that it will go first one way as 15 the needles come down, and go back when the needles are down a second time. To effect this, the shaft O , which drives the shuttle-carrier h , is geared to the main shaft L in such a manner that the former will make one revolution while the latter makes two. The shuttle-carrier h is connected by a pivot, i , to 20 one end of a lever, P , which is pivoted at j to an oscillating arm, Q , while its other end is pivoted in a sliding box which is guided in the 25 ways l . From the shuttle-carrier h extend rods $m m$, which are connected to the oscillating arm by pivots $n n$, situated on opposite sides of the pivot j , while the connections between these rods and the shuttle-carrier h are 30 formed by pivots $n' n'$, situated on opposite sides of the pivot i , which connects the shuttle-carrier to the lever P . If the rods $m m$ are made of rigid material, only one such rod is required; but if cords are used in place of the 35 rigid rods, both are needed. The oscillating arm Q is mounted on one end of a shaft, o , which has its bearing in the standard R , secured to the main frame, while on the other end of this shaft is secured a crank, S , from which 40 projects a stud or roller, p , which engages the slotted end of a lever, T , turning on a pivot, q , extending from the standard R . Near the center of the lever T is mounted a roller, r , which is engaged by the groove in the cam U , 45 mounted on the shaft O . It is obvious that as the cam U revolves, the lever T will oscillate on its pivot and impart a similar motion to the arm Q , to which the lever P is pivoted. This will cause the shuttle-carrier h , which is 50 secured to this lever, to pass back and forth in a straight line, carrying the shuttle through the loops formed by the sewing mechanism in the usual way.

In the example shown in the drawings, in 55 which the needles act as punches, making it necessary to have dies to co-operate with these punches formed in the signature-carrier, I make the latter of two parts or wings, $F' F^2$, one of which is rigidly secured to the plate b , 60 Figs. 8 and 9, while the other is connected to the same by the pivot a^3 . Between the wings F' and F^2 is a recess, A^2 , in which the loops of the needle-thread are formed, and through which the shuttle is carried in order to form 65 the stitch. When the shuttle has passed through the signature-carrier, the latter is opened in such a way that the shuttle-thread,

which then lies in the loops of the needle-thread, can be drawn out of the signature-carrier as the needle-thread is drawn up taut by 70 the sewing mechanism. When this has been done, the signature-carrier is again closed and is free to recede to its outer position to receive a new signature. It must, however, be understood that it is necessary to make the wings 75 of the signature-carrier movable only when dies for punching are formed in the same. When ordinary needles are used, both wings of the signature-carrier may be rigidly fastened to the plate b , and sufficient space left between 80 them to permit the drawing up of the shuttle-thread. The shuttle rests at each end of its stroke to permit the back and forward motion of the signature-carrier.

In Figs. 8 and 9 are indicated the two positions of the signature-carrier, as described above. From the movable wing F^2 projects an arm, b^3 , which is acted on by a latch-plate, c^3 , secured to an arm, d^3 , projecting from the needle-bar M . This latch-plate is secured to the arm d^3 by pins e^3 , working in slots f^3 in said latch-plate. Fig. 9 shows the signature-carrier closed, the needle-punch ready to descend, and the latch-plate resting on the arm b^3 . As the arm d^3 descends with the needle-bar, the latch-plate will slide inward and out of the way of the arm b^3 until it has passed said arm, when it will again fall outward by its own weight. Fig. 8 shows the needle ascending, the latch-plate in its outer position acting on the arm b^3 , and the signature-carrier opened, in which position it will remain until the arm d^3 has reached the end of its upward stroke, when the arm b^3 will slip off the lower edge of the latch-plate, and signature-carrier 100 be closed by the action of the spring g^3 , ready for a new operation.

The inner surface of the wing F' of the signature-carrier is provided with recesses a^2 , into which the needles pass as they come down, 110 and which guard them from the shuttle as the latter passes through the signature-carrier. (See Fig. 3.)

One end of the needle-thread, which in this machine is the band onto which the signatures are sewed, is secured to a block, V , and as the needle recedes after the passage of the shuttle this thread is drawn taut by the take-up. The signature on the carrier is now attached to this band by the shuttle-thread, and 120 when the latter recedes the sheet will not be carried back with it, but remain suspended from the band. Openings b^2 , Figs. 3, 8, and 9, in the side of the stop-plate serve as thread-guides, through which the thread passes on its 125 way to the needle.

After the needles have performed their sewing operation, and before the signature-carrier can move to its outer position, it is necessary to release the latter by withdrawing the spring-bolt e . This is done by a tumbler, c^2 , pivoted to the lower end of a rod, d^2 , secured to the needle-bar M . Just before the needle-bar reaches the end of its upward stroke the rod 130

d^2 and the tumbler c^2 will be in the position shown in dotted lines in Fig. 4. As the upward motion of the needle-bar continues, this tumbler, which is held in that position by the 5 pin e^2 , will press against the nose f^2 on the spring-bolt, forcing the same back and out of connection with the plate b of the signature-carrier, leaving the same free to the action of the bell-crank lever H . It will be understood 10 from the drawings that when the needle-bar descends the tumbler will strike the nose f^2 , and as it is free to turn in that direction it will fold in and not act on the bolt.

What I claim as new, and desire to secure by 15 Letters Patent, is—

1. In a sewing-machine for books, the combination, with the signature-carrier and the dies formed therein, of punches constructed to co-operate with said dies, substantially as 20 shown and described.

2. The combination, with the punches having needle-eyes formed therein, of a signature-carrier made in two sections and having dies formed therein, and mechanism for opening 25 and closing the same, substantially as shown and described.

3. The combination, with the sectional signature-carrier having the dies formed therein, of punches constructed to co-operate with said dies and having needle eyes and thread-protecting grooves extending upward from the needle-eyes on both sides of the punches, substantially as shown and described.

4. The combination, with the sectional signature carrier having the dies formed therein, of punches constructed to co-operate with said dies and provided with needle-eyes formed in said needle-punches, and a reciprocating shuttle, substantially as shown and described.

40 5. The combination, with vertically-reciprocating needles and the reciprocating signature-carrier having openings for the passage of the needles, of a swinging lever having at its upper end an attached shuttle-carrier, a vertically-movable slide to which the lever is pivoted, and mechanism, substantially as described, for operating the lever and moving its upper end and the shuttle-carrier in a true horizontal line.

50 6. The combination, with the signature-carrier having the dies formed therein, of means, substantially as shown, for imparting to the signature-carrier a reciprocating motion, the stop-plate A' , and the punches constructed 55 to co-operate with the dies in the signature-carrier, substantially as shown and described.

7. The combination, with the sectional signature-carrier having the dies formed therein, of means, substantially as shown, for impart-

ing to the signature-carrier a reciprocating motion, the stop-plate A' , needle-punches constructed to co-operate with the dies in the signature-carrier, and a reciprocating shuttle, substantially as shown and described.

8. The combination, with the signature-carrier having the dies formed therein, of means, substantially as shown, for imparting to the signature-carrier a reciprocating motion, the stop-plate A' , and the punches constructed to co-operate with the dies in the signature-carrier, the stop-plate being provided with guides 70 for the punches, substantially as shown and described.

9. The combination, with the sectional signature-carrier having the dies formed therein, of means, substantially as shown, for imparting to the signature-carrier a reciprocating motion, the stop-plate A' , having thread-guides b^2 , needle-punches constructed to co-operate with the dies in the signature-carrier, 80 and guides for the punches.

10. The combination, with the sectional signature-carrier having the openings g , forming dies, and provided with the longitudinal recess A^2 , and vertical recesses a^2 , forming 85 needle-guards, which are open to said longitudinal recess, of needle-punches constructed to operate with said dies, a shuttle, and mechanism, substantially as described, for imparting to the same a reciprocating motion through 90 said longitudinal recess.

11. The combination, with a signature-carrier and the gudgeons projecting from its sides, of reciprocating arms D , engaging said gudgeons, the arms e , firmly secured to said 95 gudgeons, projections d , formed on said arms, and the cam G , constructed to engage said projections, substantially as shown and described.

12. The combination, with the signature-carrier, of the stop-plate, the latch constructed 100 to retain the signature-carrier in its inner position, and the needle-bar arranged to release said latch, substantially as shown and described.

13. The combination, with the sectional signature-carrier, the dies formed therein, the needle-punches, the bar supporting said needle-punches, and the reciprocating shuttle, of the latch-plate c^2 and the arm b^2 , extending 105 from the movable wing F^2 of the signature-carrier, substantially as shown and described.

In testimony whereof I have hereunto set my hand and seal in the presence of two subscribing witnesses.
